INVENTOR:

LAWRENCE P. TAYLOR,

By *John W. Lewis*

ATTORNEY.

UNITED STATES PATENT OFFICE.

LAWRENCE P. TAYLOR, OF LOS ANGELES, CALIFORNIA.

APPARATUS FOR CEMENTING SOLES TO SHOES.

Application filed September 8, 1925. Serial No. 54,986.

This invention relates to a novel method of cementing soles to shoes and also to a device for conducting this method.

When shoes are worn, it is common to have them resoled. It is general practice to attach the new soles to shoes either by nailing or by sewing. When a new sole is nailed to the shoe the inner sole thereof is damaged, and when a new sole is sewed to

10 the shoe the welt thereof is damaged.

It is an object of this invention to provide a method of soling shoes which does not damage the welts of inner soles of the shoes but which involves cementing the soles in place.

It is another object of this invention to provide a method of the character mentioned in which the new sole is held pressurably in engagement with the shoe while the cement employed for the attachment of the sole is setting.

It is another object of this invention to provide a device for conducting this method.

It is also an object of this invention to provide a shoe soling device having a pliable bag filled with a mobile substance, this preferably being a liquid against which a shoe is forced after it has had a sole properly placed against the inner sole thereof, while the cement used is setting.

It is a further object of this invention to provide a shoe soling device having a novel form of box for holding the pliable bag.

35 It is a further object of this invention to provide a pliable bag having refilling means.

It is another object of this invention to provide a shoe soling device having an insert form which is placed in the shoe, this 40 insert form being designed so that the pressure may be effectively applied to the bottom of the shoe and the sole.

It is another object of this invention to provide a shoe soling device having an insert form which is expansible and has an extending rim so that pressure may be applied to the extremities of the bottom of the shoe and the sole.

50 Other objects and the advantages of the invention will appear in the following description.

Referring to the drawing in which I illustrate my invention,

Fig. 1 is a plan view of the shoe soling device of my invention. 55

Fig. 2 is an elevational view partially sectioned showing the shoe soling device of Fig. 1.

Fig. 3 is a section taken on the line 3—3 of Fig. 2.

Fig. 4 is a section taken on the line 4—4 of Fig. 2.

The form of my invention shown in the drawing comprises a table or base plate 11 having an upper face 12 from which there extend posts 13, these posts 13 being rigidly secured to the table 11 as by threaded projections 14 extending into cavities of the table 11, as shown in Fig. 2. Upper reduced ends 16 of the vertical post 13 extend through openings 17 formed at the opposite ends of a head 18. Nuts 19 are threaded onto the projecting ends of the reduced ends 16 for clamping the lower face of the head 18 against annular shoulders 21 of the post 13. The head 18 has a threaded passage 22 through which a screw 23 extends, this screw 23 having a hand wheel 25 by which it may be rotated and advanced in either direction and having a shoe 27 attached at the lower end thereof.

A bag retaining box 29 is supported on the upper face 12 of the table 11. This box 29 has a bottom wall 30 from which there extend in an upward direction end walls 31 and side walls 32. The side walls 32 are declined at the left end thereof, as indicated at 33 in Fig. 2, so that the left end wall 31 is somewhat shorter than the right end wall 31. A continuous retaining lip 36 extends inwardly from the upper ends of the side and end walls 31 and 32.

Placed in the box 29 is a pliable bag 38 which is filled with a non-compressible liquid 39 or with some other mobile, pressure-transmitting substance, if desired. This pliable bag 38 consists of an inner flexible impervious bag 41 which is enclosed by a protective covering 42 which is preferably made from canvas. The bag 38 is placed in the box 29, as shown in Figs. 2 and 3. The bag 38 may be filled with the non compressible liquid 39 by means of a valve 43 which extends therefrom through an opening 44 in a side wall 32 of the box 29. When the bag is filled with liquid, as shown in the draw-

ing, it is caused to follow the contour of the inner faces of the bottom and side walls and the retaining lip 36 of the box. The retaining lip 36 provides a shoulder which retains 5 the bag 41 in place in the box 29.

An insert form 46 is provided in my invention, this insert form 46 having halves 47 which may be expanded sidewise with relation to each other by operating a threaded stem 48. This operating stem 48 is associated with a common type of spreading arrangement and it is not necessary to show the details thereof. The insert form 46 comprised of the halves 47 has a foot portion 49 from which there extends a rim 50 as shown in Figs. 3 and 4. Extending forwardly from the upper parts of the halves 47 are arms 52.

The insert form 46 is placed in a shoe 54, 20 as shown in Figs. 2 and 3. The shoe 54 has been previously worked upon and has a new sole 55 temporarily held in engagement with the lower face of a bottom or inner sole 56 of the shoe 54 as by a single nail. The 25 lower face of the inner sole 56 is coated with a suitable cement and the upper face of the sole 55 is likewise coated with a suitable cement before these faces are brought into engagement. The insert form 46 is extended 30 into the forward part of the shoe 54 and the halves 47 are expanded sidewise, as shown in Fig. 3, so that the rim 50 will extend to the extremities of the inner sole 56. The insert form 46 may be held in the 35 forward part of the shoe by means of an adjustable arm 58 which extends rearwardly from the insert form 46 and has an engager 59 secured at the end thereof, which engager 59 is adapted to contact a rear part of the 40 shoe 54.

After the form has been thus installed in the shoe 54, this shoe and form are placed as shown in Figs. 2 and 3 of the drawing. The lower face of the sole 55 is placed on the 45 upper part of the pliable bag 38 and the arms 52 are positioned below the threaded shoe 27 of the screw 23. The screw 23 is then advanced downwardly by operating the hand wheel 25 so that the threaded shoe 27 will engage the arms 52 and force the form 50 in a downward direction. This forces the form against the inner sole 56 of the shoe 54 and forces the sole 55 firmly against the pliable bag 38. As shown clearly in Fig. 3 the bag 38 readily conforms to the contour of the inner sole and the bottom of the form 46, and the sole 55 is forced into conformity with this shape. The liquid 39 in the bag 38 55 exerts a force upwardly against the sole of the shoe 55, which force is distributed evenly over the area of the sole.

As shown in Fig. 2 the side walls 32 of the box 29 are declined so as to make room for the heel of a shoe. In cementing soles to ladies' shoes it is necessary for the bag to

follow the contour of the bottom of the shoe up into the space adjacent to the heel. By declining the side walls 32 it is possible to allow the heel to rest over the bag and for the bag to readily follow the contour of the 70 bottom of the shoe. The cement is allowed to set while the sole 55 and the inner sole 56 are held pressurably in engagement with each other and while the sole 55 is caused to conform to the contour of the bottom of 75 the shoe. After the cement has properly set, the screw 23 is retracted and the form 46 may be removed from the shoe 54.

In practice I have found that I am able 80 to perform superior workmanship by the method of my invention and by use of the device shown in the drawings. My invention does not damage the shoe in any way and consequently the shoe may be resoled a great 85 number of times. When soles are nailed to the shoe and when sewed to the shoe, the inner sole or the welts are damaged each time and consequently the life of the shoe is considerably shortened. The shoe soled in the fashion of my invention is found to be 90 very flexible and will retain its shape. When sewing and nailing soles to shoes, the shape 95 of the shoe is often distorted.

I claim as my invention:

1. A device for attaching soles to shoes comprising: a pliable bag filled with non-compressible liquid; a box for supporting said pliable bag, said box having an inward projecting rim for holding said pliable bag in said box; an insert form adapted to be inserted in a shoe, said insert form having a rim and being expansible so that said form may be extended to the extremities of the bottom of said shoe, said shoe having cement applied to the bottom and having a sole with cement applied thereto temporarily attached to the bottom thereof; and means engaging said insert form in a manner to exert a pressure against the inner surface of the bottom of said shoe and to force said sole against said pliable bag while said cement sets, said pliable bag conforming to the shape of the bottom of said shoe and exerting a pressure against the bottom of said sole which is equal at all points.

2. A device for attaching soles to shoes comprising: a pliable bag filled with non-compressible liquid; a box for supporting said pliable bag, said box having an inward projecting rim for holding said pliable bag in said box; an insert form adapted to be inserted in a shoe, said insert form having a rim and being expansible so that said form may be extended to the extremities of the bottom of said shoe, said shoe having cement applied to the bottom and having a sole with cement applied thereto temporarily attached to the bottom thereof; a table adapted to support said box; posts extending upward from said table; a head sup-

ported at the upper end of said posts; and a screw carried by said frame engaging said insert form in a manner to exert a pressure against the inner surface of the bottom of 5 said shoe and to force said sole against said pliable bag while said cement sets, said pliable bag conforming to the shape of the bottom of said shoe and exerting a pressure against the bottom of said sole which is 10 equal at all points.

3. A device for attaching soles to shoes comprising: a closed pliable bag filled with non-compressible liquid; means whereby said pliable bag may be refilled; a box for 15 supporting said pliable bag, said box having an inward projecting rim for holding said pliable bag in said box; an insert form adapted to be inserted in a shoe, said insert form having a rim and being expansible so 20 that said form may be extended to the extremities of the bottom of said shoe, said shoe having cement applied to the bottom and having a sole with cement applied thereto temporarily attached to the bottom there- 25 of; a table adapted to support said box;

posts extending upward from said table; a head supported at the upper end of said posts; and a screw carried by said frame engaging said insert form in a manner to exert a pressure against the inner surface 30 of the bottom of said shoe and to force said sole against said pliable bag while said cement sets, said pliable bag conforming to the shape of the bottom of said shoe and exerting a pressure against the bottom of 35 said sole which is equal at all points.

4. A combination as defined in claim 3 in which said insert form has arms which extend forwardly, said arms being engaged by said screw and being so extended that pressure may be effectively applied to the inner surface of said shoe. 40

5. A combination as defined in claim 3 in which one end of said box is declined to make ample room for the heel of a shoe. 45

In testimony whereof, I have hereunto set my hand at Los Angeles, California, this 31st day of August, 1925.

LAWRENCE P. TAYLOR.
